UNITED STATES PATENT OFFICE.

JOSEPH F. HIGGINS, OF NEW YORK, N. Y.

BLINDSTITCH TAPING ATTACHMENT FOR SEWING-MACHINES.

1,195,814.

Specification of Letters Patent. Patented Aug. 22, 1916.

Application filed February 9, 1915. Serial No. 7,006.

To all whom it may concern:

Be it known that I, JOSEPH F. HIGGINS, a citizen of the United States, and a resident of the city of New York, borough of Brooklyn, in the county of Kings and State of New York, have invented a new and Improved Blindstitch Taping Attachment for Sewing-Machines, of which the following is a full, clear, and exact description.

10 This invention relates to an attachment for double needle or single zigzag stitch sewing machines, whereby tape, braid and the like may be applied to cloth or other fabric by blind stitching.

15 The invention has for its general objects to provide a novel, simple and inexpensive attachment for sewing machines, whereby taping with invisible stitches can be easily, quickly and effectively accomplished, the feed of the tape being entirely automatic so that the application of the tape to a fabric is as simple as making an ordinary seam or hem with a sewing machine.

20 A further object of the invention is the provision of a guide and folder which is attached to the presser foot of the sewing machine and by means of the same the tape has its edges symmetrically folded, and the tape passes through the needle opening of 25 the presser foot and moves backwardly under the same with the fabric to which the tape is sewed, the needle or needles being disposed within the tubular part of the tape between the folder and needle opening of 30 the presser foot, whereby the needles pass through the inturned edges of the tape at 35 the point where the tape is laid against the fabric.

With such objects in view, and others 40 which will appear as the description proceeds, the invention comprises various novel features of construction and arrangement of parts which will be set forth with particularity in the following description and 45 claims appended hereto.

In the accompanying drawing, which 50 illustrates one embodiment of the invention, and wherein similar characters of reference indicate corresponding parts in all the views, Figure 1 is a perspective view of the presser foot and needle bar of a double needle machine with the taping attachment applied to the presser foot; Fig. 2 is a vertical section on the line 2—2, Fig. 3, drawn 55 on an enlarged scale; Fig. 3 is a section on the line 3—3, Fig. 2; Fig. 4 is a perspective

view showing the manner in which the tape is folded preparatory to the stitching of the same on a fabric; Fig. 5 is a plan view of a blind stitched tape sewed by a double needle 60 machine; Fig. 6 is a similar view showing a tape sewed by a zigzag needle machine; Fig. 7 is a plan view of the tape folder; and Fig. 8 is a sectional view of the lower end of the tape folder. 65

Referring to the drawing, A designates the presser foot of a sewing machine and B the needle bar which is shown in the present instance as having two needles 1 and 1^a which reciprocate in the needle opening 2 70 of the presser foot. The attachment includes a folder or former C which is disposed above and adjacent the needle opening 2, so as to cause the tape D to assume a tubular form as it feeds through the needle 75 opening to the fabric E on which the tape is blind stitched.

The tape D can be fed from a spool or reel suitably mounted on the machine, and it passes forwardly through a guide opening 3 80 in the shank 4 of the presser foot, and between this opening and the folder C is a guide 5 formed of wire and secured by a screw 6 to the presser foot. The folder C is made of sheet metal and comprises a base 85 7 fastened to the presser foot by a screw or equivalent device 8, and a shank 9 extends forwardly from the base and carries the folding means at its forward end. The folding means is formed by oppositely extending 90 flanges 10, each of which is bent backwardly on itself to form guide passages 11. At the upper part these passages are in approximately a straight line, as shown in Fig. 7, but at the lower part of the folder they are 95 of circular disposition, as shown in Fig. 8. Thus the braid in entering the folder is approximately flat, but in leaving the folder it is of tubular form, the edges being turned inwardly toward each other by the curvature of the lower ends of the guide 100 passages 11. From the folder C the tape passes vertically into the needle opening 2 of the presser foot, and the needle or needles pass downwardly through the tubular portion of 105 the folded tape and pass through the in-folded edges of the tape, whereby the said edges are stitched to the fabric, the stitches being wholly concealed, as shown in Figs. 5 and 6. Since the folder is crotched or bi- 110 furcated the needle or needles are accommodated within the folder, and therefore the

folder can be located directly over the needle opening of the presser foot, whereby the best disposition of the folded edges of the tape with respect to the needles is had. The 5 front of the folder is provided with an opening 12, whereby the tape can be more easily inserted in the folder, and the edges of the tape engage in the hollow flanges or members 10.

10 In operation the tape passes easily and smoothly through the guides and folder and no attention is required on the part of the operator any more than the guiding of the material in a manner to stitch the tape where 15 it is desired.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire 20 to have it understood that the device shown 25 is merely illustrative and that such changes may be made when desired as are within the scope of the appended claims.

Herein the invention has been shown and 30 described as applied to a flat presser foot but it is to be understood that the same can be used with a roller presser foot, and furthermore, tapes of different widths may be sewed on fabrics by the use of the invention, 35 it being of course necessary to employ a folder and sewing machine suited to the particular width of tape desired.

Having thus described my invention, I claim as new and desire to secure by Letters 40 Patent:

1. The combination of a presser foot having a needle opening, one or more needles adapted to move vertically into and out of the opening, a guide associated with the 45 presser foot and through which a tape is adapted to pass, and a former associated with the presser foot and disposed between the guide and needle opening, said former having spaced curved members by which the

edges of the tape are inturned, and whereby 50 the tape lying between the former and the needle opening of the presser foot assumes approximately a tubular form, said former being so positioned with respect to the needle or needles that the needles operate within 55 the former to penetrate the inturned edges of the tape and sew the same to a fabric.

2. The combination of a presser foot having a needle opening, a folder attachment secured to the presser foot and including a 60 pair of oppositely disposed hollow flanges forming guide passages, the upper part of the flanges being approximately straight and the flanges curving progressively downwardly, whereby the lower ends form a flat 65 tape into a tube, with the edges in proximity, the lower portions of the flanges being directly above the needle opening of the presser foot for guiding the folded tape into the opening, and one or more needles 70 extending downwardly between the lower curved portions of the hollow flanges of the folder and vertically to and through the needle opening, whereby only the infolded edges of the tape may be stitched to a body 75 fabric.

3. The combination of a presser foot having a needle opening, means on the presser foot for guiding a tape, a folder mounted on the presser foot and having a folding 80 means located between the opening of the presser foot and the first-mentioned means, said folding means comprising a device for changing a flat tape into tubular form and maintaining the tubular portion of the tape 85 at the needle opening vertical, and a needle or needles disposed in the said folder and adapted to pass into the needle opening of the presser foot, whereby the infolded edges of the tape may be stitched to a body fabric. 90

In testimony whereof I have signed my name to this specification in the presence of two subscribing witnesses.

JOSEPH F. HIGGINS.
